Primary Examiner — Jennifer L Rempfer*Assistant Examiner* — Adrienne Corra(74) Attorney, Agent, or Firm — Banner & Witcoff, Ltd.(57) CLAIM

The ornamental design for a shoe as shown and described.

DESCRIPTION

FIG. 1 is a bottom view of a shoe showing our new design;
FIG. 2 is a bottom front perspective view thereof;
FIG. 3 is a bottom rear perspective view thereof;
FIG. 4 is a side view thereof; and,
FIG. 5 is an opposite side view thereof.

The broken lines immediately adjacent to the shaded area define the bounds of the claimed design and form no part thereof. The broken lines depicting the remainder of the shoe form no part of the claimed design.

1 Claim, 5 Drawing Sheets(56)
